UNITED STATES PATENT OFFICE.

EVERARD BLACKSHEAR, OF CITRA, FLORIDA.

HAIR-CURLER.

1,203,964.

Specification of Letters Patent. Patented Nov. 7, 1916.

Application filed June 1, 1916. Serial No. 101,085.

To all whom it may concern:

Be it known that I, EVERARD BLACKSHEAR, a citizen of the United States, residing at Citra, in the county of Marion, State of Florida, have invented a new and useful Hair-Curler; and I do hereby declare the following to be a full, clear, and exact description of the invention, such as will enable others skilled in the art to which it appertains to make and use the same.

This invention relates to an improved hair curler, and particularly to improved means for detachably connecting or locking the extremities of the opposite arms of the curler together.

One of the objects of the invention is to provide improved means, whereby the terminals of the spring arms of the curler may be detachably connected, including means to prevent lateral movement of the arms relatively to each other.

Another object of the invention is to provide a curler constructed from a single strip of sheet spring steel, so bent and otherwise constructed that the terminals of the arms of the curler may be detachably connected.

In practical fields the details of construction may necessitate alterations, falling within the scope of what is claimed.

The invention comprises further features and combination of parts, hereinafter set forth, shown in the drawings and claimed.

In the drawings:—Figure 1 is a view in perspective of the improved curler constructed in accordance with the invention. Fig. 2 is a longitudinal sectional view. Fig. 3 is an enlarged detail view of the two ends of the arms of the curler. Fig. 4 is a transverse sectional view on the line 4—4 of Fig. 3. Fig. 5 is a perspective view of another form of curler. Fig. 6 is a perspective view of another form of the curler.

Referring more especially to the drawings, 1 designates the curler as a whole, which is constructed of a single length of sheet spring metal bent upon itself, as shown at 2, thereby forming two oppositely disposed arms 3 and 4. The arm 3 at its terminal is bent upon itself to form a loop 5, the extremity of this bent portion being riveted at 7 near the end of said arm. The loop itself is bent over to form a shoulder 9, under which the extremity of the arm 4 engages, thereby holding the two arms together. When the arms are separated and

their extremities detached, the arms diverge from each other. Therefore, it will be noted that when the arms are brought together, whereby their terminals may be connected, 60 they are forced yieldably toward each other. Extending from the edges of the arms 3 upon opposite sides of said loop, are two ears 10 which are so disposed toward the shoulder formed by the loop as to prevent 65 lateral movement of the arm 4. In Fig. 5 these ears are dispensed with.

In Fig. 6 the loop at the extremity of the arm 3 is constructed from a separate piece of spring metal, which is bent upon itself 70 to form said loop 5^a, which is, in turn, bent on itself to form the shoulder. The end portions of the separate piece of metal from which the loop 5^a is constructed are riveted at 11 to the extremity of the arm 3. 75

When curling hair, the hair may be wrapped on one of the arms to form a roll, and then the other arm may be detachably connected to the extremity of the first arm, thereby holding the hair rolled, allowing the 80 same to remain in this state for a while, after which the arms may be detached and the hair unwound, which will be in a curled condition.

If desired, the hair may be rolled on the 85 finger, and the finger afterward removed, to permit one of the arms of the curler to be inserted through the roll, after which the arms may be connected at their extremities.

To close the jaws or arms 3 and 4 of the 90 curler, the loop 2 may be held in the left hand, between the thumb and the first finger, whereas the opposite edges of the loop 5 may be held between the thumb and the second finger of the right hand, then by 95 bowing the arm or jaw 3 away from the arm or jaw 4, and finally using the first finger of the right hand to press the jaw 4 toward the arm or jaw 3, in which case the free end of the jaw or arm 4 will engage 100 under the loop 5, that is, when applying a little force or pressure against the arm or part 4. To open the arms or jaws, it is only necessary to bow or bend the arm, jaw or part 3, and the free end of the arm or jaw 105 4 will spring from under the loop 5.

The invention having been set forth, what is claimed as new and useful is:—

A new article of manufacture consisting of a curler constructed of a single length 110 of elongated spring sheet metal bent upon itself substantially midway its ends form-

ing arms which are bent laterally from each other and diverging, the terminal portion of one of the arms being bent upon itself to form a loop, the extremity of said 5 bent portion being riveted to the arm, said loop being bent upon itself to overlie the extremity of the other arm, when pressed toward the first arm, the extremity of the arm having a loop being provided with ears 10 bent toward and adjacent the sides of the

loop, thereby preventing lateral movement of the arm with its extremity underlying the loop.

In testimony whereof I have signed my name to this specification in the presence of 15 two subscribing witnesses.

EVERARD BLACKSHEAR.
